UNITED STATES PATENT OFFICE.

WILLIAM WALLACE DYMOND, OF CARBONDALE, KANSAS.

ROPE-KNIFE GUIDE.

Application filed April 5, 1923. Serial No. 629,986.

To all whom it may concern:

Be it known that I, WILLIAM WALLACE DYMOND, a citizen of the United States, and resident of Carbondale, county of Osage, 5 State of Kansas, have invented a certain new and useful Improvement in Rope-Knife Guides, of which the following is a complete specification.

This invention relates to rope knife guides 10 and my object is to produce a tool for oil well and other purposes, for use with a sand line whereby the tool line may be sufficiently and readily secured close to the tools regardless of the depth of the well and diameter of the casing, when the tools have 15 become wedged in the hole and it is necessary to fish them out.

With the present tools, it is found extremely difficult in deep wells using small 20 size casing such as 6 $\frac{1}{2}$ and 8 $\frac{1}{4}$, when it is desired to remove the tool line after the tools have become wedged in the bottom of the hole, to lower a rope knife into such 25 deep well without the rope knife or sand line entangling and becoming twisted with the tool line which it is desired to remove.

The entanglement above mentioned has 30 been discovered to be due to the fact that the rope knife, jars and sinker will often rotate in the casing and, even when a swivel is employed, will become twisted around the tool line so that force applied for cutting the tool line is actually expended in clamping the sand rope upon the tool rope without 35 in any way applying cutting action thereon.

The primary object of the invention, therefore, is to provide a knife guide which 40 will efficiently prevent the turning action of the knife and carrying tools and rope within the casing.

With the object named in view, the invention consists in certain novel and useful features of construction and organization 45 of parts as hereinafter described and claimed; and in order that it may be fully understood, reference is to be had to the accompanying drawing, in which:—

Figure 1 is a central vertical section taken 50 through an oil well casing and illustrates the relation the tool of the invention will bear to the other parts of a rope knife suspended by a sand line into a well;

Figure 2 is an enlarged section on the 55 line II—II of Figure 1;

Figure 3 is a section on the line III—III of Figure 2;

Figure 4 is a section on the line IV—IV of Figure 3;

Figure 5 is a face view of the tool; and 60

Figure 6 is a perspective view of one of the carrier guides forming a part of the invention.

In the said drawing, where like reference characters identify corresponding parts in 65 all of the figures, 1 represents the oil well casing, shown in two sections coupled together by a coupling 2, the upper and lower casing sections not being screwed into abutting relation but leaving a space 3, as often 70 occurs in the placing of a casing section.

The tool line, which it is desired to sever, is indicated at 4, the sand line used to support the rope knife is indicated at 5, said sand line having a swivel connection 6 with 75 the upper end of a sinker 7, secured at its lower end to the customary jars 8, which in turn suspends the rope knife 9. All of the parts above-referred to are of any common or preferred construction. 80

The tool of the invention consists of a pair of carriers 10, see Figure 6, comprising vertical back portions, top and bottom portions 11, and side wings 12. Each of said casings in the tool, as illustrated, is 85 welded or otherwise fixedly secured to and between a pair of side plates 13, which are provided at suitable points with threaded openings for engagement by cap screws 14, which secure the parts above described in 90 position between and at opposite ends of a pair of clamp plates 15, it being noted that the carrier guides are spaced apart a sufficient distance to provide an opening 15^a of 95 width slightly greater than the diameter of any sinker rod with which the tool is intended for use.

Slidably mounted in each of the carrier guides 10 are carriers 16, it being noted in this connection that the frictional engagement of the sides of the carriers with the guides will be relatively small as such engagement will be with the wings 12 alone. The outer corners of each of said carriers are bifurcated as at 17 for the reception of 105 knife-edge rollers 18 journaled on pins 19 mounted in the carriers. Each of the carriers is formed on its rear face with a pair of protuberances 20 carrying expansion springs 23 pressing against the back of the 110

carrier guide 10. The carriers are limited, both as to outward and inward movement, by a pair of screws 24 which project through slots 25 formed in the top and bottom 11 5 of the carrier guide 10.

In the use of the device one of the side plates 15 is removed from position and the sinker rod 7 is received within the space 15^a thus made accessible, the plate 15 is then 10 returned to position and the tool is fixedly clamped to the sinker rod 7 by means of a series of clamp screws 26.

The rope knife is now applied to the tool line and with its accompanying devices are 15 now lowered into the well, the springs 23 permitting the carriers 16 to be repressed sufficiently to permit the tool to enter the top of the casing, the springs 23 immediately pressing the carriers outwardly and thus 20 engaging the knife-edge rollers 18 with the interior of the casing at diametrically opposite points. The rope knife is now lowered as common in the art until the knife is arrested by contact with the drilling tools suspended by contact with the drilling tools suspended by the line 4. It will be apparent 25 from a consideration of the device as described and illustrated, that if the springs 23 are sufficiently stiff, the knife rollers will strongly press against the wall of the casing 30 and will overcome any tendency the rope knife and its accessories may have to turn or twist within the casing.

The tool is so proportioned that when a space 3, between the ends of adjacent casing sections is encountered, one of each pair of rollers will always be in contact with the casing wall, and will thus prevent any possibility of a single roller of either pair entering the space far enough to become 40 wedged and prevent further downward movement of the cutting tools, and also, that by retaining one of each pair of rollers in contact with the casing, while the other rollers are passing the space 3 that there is 45 no chance for any twisting or turning movement of the guide and string of cutting tools.

With the parts arranged as explained, it will be apparent that upward force applied 50 on the sand line will be transmitted directly to the cutting elements of the knife and that the proximity thereof to the drilling tools will effect the severance of the tool line in close proximity to the tools, and that 55 when this is accomplished the sand line and its equipment is removed to permit fishing tools to be employed in the customary manner for effecting the removal of the drill-

ing tools. It will also be noted that the guide does not interfere with the tool line other than to simply press it to one side as indicated most clearly in Figures 2 and 4. 60

It is believed that the construction and operation of the tool has been sufficiently set out as to make further recapitulation of the 65 operation unnecessary. It is desired to state, however, that the length of the slots 25 in the carrier guides and the proportion of the parts of each tool may be such as to accommodate well casings of varying diameter within certain limits, as will be readily understood.

It will be evident from the above description that I have produced a tool of the character described which possesses all of 75 the features of advantage pointed out as desirable, and while I have described and claimed the preferred embodiment of the same, I reserve the right to make all changes 80 properly falling within the spirit and scope 85 of the appended claims.

I claim:

1. The combination with a well casing, of a rope-suspended tool within the casing, and a guide carried by the tool and comprising 85 a body portion, spring-advanced carriers mounted in the body at diametrically opposite sides thereof, and a pair of rollers spaced vertically apart and journaled on and projecting beyond the carriers and engaging 90 the casing.

2. The combination with a well casing, of a rope-cutting mechanism therein and engaging a rope to be cut, a rope suspending such mechanism within the casing, and a 95 guide mounted on said cutting mechanism, and comprising a body portion, carriers radially adjustable thereon with respect to the casing, a pair of vertically suspended edge-rollers journaled on and at the outer sides 100 of each carrier, and springs interposed between the body portion and the carriers to hold said rollers in contact with the casing.

3. A guide, comprising a body portion, a pair of carriers oppositely mounted in said body portion, a plurality of spaced rollers carried by each of said carriers and projecting beyond the same, and a series of springs 105 for each of said carriers pressing at one of their ends against the body portion and at 110 their other ends against their respective carriers.

In witness whereof I hereunto affix my signature.

WILLIAM WALLACE DYMOND.
